TOY TRUCK

Ira B. Gilford, Thousand Oaks, Calif., assignor to Mattel,
Inc., Hawthorne, Calif., a corporation of Delaware

Filed Feb. 2, 1970, Ser. No. 21,179

Term of patent 14 years

Int. Cl. D21—02

U.S. Cl. D34—15

FIG. 5

FIG. 6

FIG. 1

FIG. 2

FIG. 7

FIG. 8

FIG. 3

FIG. 4

FIG. 1 is a perspective view of a toy truck showing my new design in the form of an ambulance, the opposite side being substantially the same;

FIG. 2 is a perspective view of the FIG. 1 truck wherein a tow truck body has been substituted for the ambulance body portion, the opposite side being substantially the same;

FIG. 3 is a top plan view of the FIG. 1 truck with the body portion removed;

FIG. 4 is a bottom plan view of the truck;

FIG. 5 is a front elevational view of the truck with the body portion removed;

FIG. 6 is a rear elevational view of the truck with the body portions removed;

FIG. 7 is a front perspective view of the truck with the body portion removed; and

FIG. 8 is a right side elevational view of the truck with the body portions removed, the opposite side being substantially identical.

I claim:

The ornamental design for a miniature toy vehicle, as shown.
